HANGER FOR OBJECT CARRYING BALES

Filed Oct. 17, 1927

UNITED STATES PATENT OFFICE.

FREDERICK B. LITTLE, OF CHICAGO, ILLINOIS, ASSIGNEE TO J. C. DEAGAN, INC., OF CHICAGO, ILLINOIS, A CORPORATION OF ILLINOIS.

HANGER FOR OBJECT-CARRYING BAILE.

Application filed October 17, 1927. Serial No. 226,746.

My invention relates to hangers for object carrying baile and is of particular utility when employed in connection with musical instruments that contain sound producing 5 bars that depend from such baile.

The invention has for its objects the provision of means whereby the heights of the baile may be regulated and the baile may be positioned to substantially fix the planes in 10 which they are disposed.

In carrying out my invention I employ a mounting and a bail supporting button upon and vertically adjustable with respect to said mounting. The button is desirably provided with one or more grooves in which the bight of the supported bail is received. The button is desirably rendered vertically adjustable by having suitable connection with the mounting.

20 The invention will be more fully explained in connection with the accompanying drawing in which Fig. 1 is a side view of the preferred embodiment of the invention as used in connection with a sound producing instrument, one form of a circuit arrangement being also illustrated; Fig. 2 is a plan view of the structure shown in Fig. 1; Fig. 3 is a sectional view on line 3—3 of Fig. 1; Fig. 4 is a perspective view of a bail supporting button; and Fig. 5 is a view of a part of the structure on line 5—5 of Fig. 3.

The instrument illustrated is a percussion instrument employing a hammer and a vibrating bar which may be struck by the hammer when a sound is to be produced by the bar, both the bar and hammer having a common support. The hammer illustrated includes a rod having a rear portion 1 which is made of iron and constitutes the core of a solenoid 35 coil 2. There is another rod portion 3 which is supplied in addition to the rod portion 1 and is of smaller diameter. This rod portion 3 is at that end of the solenoid coil in the direction of which the core element 1 is moved 40 when the solenoid coil is energized, upon the closure of the switch 4 that serves to include the suitable source of current 5 in the circuit of the solenoid coil.

45 The coil is carried by a bracket 3 which is mounted upon a suitable support 7, said bracket being forwardly extended at 8 to also serve as a support for the bail 9, usually

a fiber cord or string, for the tubular bell 10 or other sound producing element. A hammer head 11 is provided upon the rod 3 and 55 serves to strike the bell 10 each time the switch 4 is closed, the hammer mechanism being desirably of the construction set forth in my copending application Serial Number 226,747, filed October 17, 1927, Case 3. The 60 quality of the tone produced by the bell, when struck, depends to a large extent upon the precise place where the hammer strikes the bell. I, therefore, have devised the hanger of my present invention which enables the sound 65 producing bell to be vertically adjusted to a position where it may be most effectively operated upon by the hammer. As illustrated, this hanger is inclusive of a mounting which comprises the bracket portion 8, a bail 70 positioner 12 below said bracket portion, and inclusive of a block portion 13 which is receivable in the slot 14 in said bracket portion, an upright threaded stem 15 carried by and projecting from the block portion 13 and extending above the bracket portion 8, and a clamping nut 16 for clamping the bail positioner in position, the slot 14 being desirably elongated to permit movement of the bell 10 longitudinally of the bracket portion 8 to 80 adjust the striking distance between the bell and hammer. A washer 17 may be interposed between the nut 16 and the bracket portion 8. The positioner 12 is provided with upright groove formations 18 in which the 85 side portions of the bail are received whereby the plane of the bail is maintained at right angles to the aforesaid bracket portion 8.

A button 19, preferably formed of rubber, is provided with a metallic sleeve 20 imbedded 90 therein, this sleeve being in threaded engagement with the threaded stem 15. The stem 15 being upright, the axis of turning movement of the button is upright whereby the height of the button may be regulated. This 95 button is formed with grooves 21 extending at right angles to each other and diametrically across the top of the button, one or the other of these grooves receiving the bight of the bail 9 according to the position to which 100 said button is turned. The button is desirably semi-globular in shape so as to conform in shape to the bight of the bail. By turning the button, its height with reference to

the bracket is adjusted so that the height of the bail 9 is correspondingly adjusted to adjust the height of the bell 10.

Changes may be made without departing 5 from the invention.

Having thus described my invention, I claim:

1. A hanger for an object carrying bail including a bail positioner having upright 10 groove formations in which the side portions of the bail are received; and a button above the positioner and screwed into assembly therewith, the axis of turning movement of the button being upright, whereby the height

of the button may be adjusted, said button 15 having a groove in its top for receiving the bight of the bail.

2. A hanger for an object carrying bail including a support; and a button above the support and screwed into assembly with the support, the axis of turning movement of the button being upright, whereby the height of the button may be adjusted, said button having a groove in its top for receiving the bight 20 of the bail. 25

In witness whereof, I hereunto subscribe my name.

FREDERICK B. LITTLE.
